UNITED STATES PATENT OFFICE.

FRANK M. PRATT, OF NEW YORK, N. Y.

SPRING-PADDING STRUCTURE.

Application filed December 9, 1927. Serial No. 238,762.

This invention relates to resilient or spring padding structures.

Resilient or spring pressed pads have many uses, one such use being in ironing machines.

5 In such machines the ironing elements, as for instance the ironing rolls, have their outer ironing surfaces provided with resilient pads to permit the surface to give or be depressed by buttons, hooks, or other projections carried by the garments passing through the machine.

10 The invention has for its salient object to provide a resilient pad structure that is simple in construction and that can be easily and quickly applied to the ironing element of an ironing machine or to any other structure at a minimum of expense.

15 Another object of the invention is to provide a resilient pad structure so constructed and arranged that the springs or resilient elements are firmly and securely held in position under tension.

20 Further objects of the invention will appear from the following specification taken 25 in connection with the drawings, which form a part of this application, and in which

25 Fig. 1 is a plan view partly broken away 30 of an ironing roll having a resilient pad structure constructed in accordance with the invention;

Fig. 2 is an enlarged sectional elevation showing the manner of securing the springs in position on the ironing roll;

35 Fig. 3 is a sectional elevation taken at right angles to Fig. 2 and substantially on lines 3—3 of Fig. 4;

40 Fig. 4 is an enlarged plan view of the structure shown in Fig. 2, the cover being removed to show the springs;

45 Fig. 5 is an elevational view showing a slightly different embodiment of the invention;

Fig. 6 is a plan view partly broken away showing another type of ironing element having a resilient pad constructed in accordance 45 with the invention; and

Fig. 7 is a detail sectional elevation of one end of the device shown in Fig. 6, Fig. 7 being taken at right angles to Fig. 6.

50 The invention briefly described consists of a resilient pad structure in which the element to which the pad is to be secured is provided with a groove or grooves and a plurality of springs are secured to the outer surface 55 of the element by securing means, such as

links, disposed in the groove or grooves. The ends of the spring structure are anchored firmly to the element on which the resilient pad is mounted. After the pad structure has been secured in position the outer ends of the 60 springs are covered by suitable sheeting or a covering of felt or other suitable material. In the particular embodiments of the invention illustrated the resilient pad structure has been shown in connection with the ironing elements of an ironing machine but it should be understood that the structure is not limited to this particular use and may be used in many other ways. For instance, the 65 springs used in upholstering furniture could 70 be secured in the manner illustrated and hereinafter described.

Further details of the invention will appear from the following description.

In Fig. 1 there is shown an ironing roll 10 75 for use in an ironing machine. The roll consists of a metallic shell 11, the outer surface of which, as shown in Figs. 1 and 2, is provided with a spiral groove 15. This groove extends spirally around the outer surface of 80 the roll from one end to the other thereof.

In the form of the invention illustrated in Figs. 1 to 4 inclusive, a plurality of sets of springs A, B, C, D, etc. are secured to the outer surface of the roll 10. Each set comprises a pair of springs 16 and 17, preferably of the spiral type, the two springs 16 and 17 being integrally connected by a portion 85 18. These sets of springs may be formed by straightening out one convolution of the 90 spring and bending the springs into parallel relation as shown in Fig. 2.

The end spring 16 of the set A is secured in position by means of a member 20 having one end 21 looped around the base of the 95 spring 16 and having its other end bent laterally as shown at 22 in Fig. 2 and secured in an aperture 23 formed in the shell 11 in any suitable manner, as by means of a screw 24. It will be noted that the securing member 20 is disposed in the groove 15.

The sets of springs are connected together by means of links 25, the ends of the links being looped around the bases of the springs of successive sets and the links, as shown in Figs. 2 and 3, being disposed in the groove 15.

After the sets of springs are connected by means of the links 25 the spring structure is wound around the roll and the links 25 are seated in the groove. The spring at the other 100 105 110

end of the spring structure is then connected to the shell by means of a member 30 similar to the securing member 20.

The spring structure can be stretched tightly around the roll as it is wound thereon, thus securing the springs firmly and securely to the outer surface of the shell under tension.

After the springs have been secured in the manner above described or in the manner hereinafter set forth, a suitable covering 35 of sheeting, felt or other suitable material is wound tightly around the outer ends of the springs.

In the form of the invention shown in Fig. 5, the springs are not secured in sets of two each but each spring 36 is secured to the adjacent springs by means of links 37 which are disposed in the groove in the same manner as the links 25 in the form of the invention already described.

In Fig. 6 a different type of ironing element is illustrated. The ironing element in this case consists of a pressing shoe or board 45 used particularly for pressing clothes. The board 45 is grooved, as shown at 46, and springs 47 are secured to the board over the grooves in the manner shown in Figs. 1 to 4 or in Fig. 5. At one end of each set of springs there is provided an eye bolt 50 having one end 51 threaded and provided with a nut 52. The eye bolt is connected to the end spring and extends through a flange 53 at the end of the board or shoe. By turning the nut the set of springs can be placed under tension and securely held in position. The springs are covered by a suitable covering 48 as in the other embodiment of the invention.

From the foregoing description it will be seen that a simple, practical and inexpensive spring pad structure has been designed and that spring padding can be easily, quickly and economically secured to any desired surface in the manner described. Furthermore, it will be clear that the springs will be firmly and securely held in place.

Although certain specific embodiments of the invention have been particularly shown and described, it will be understood that the invention is capable of modification and that changes in the construction and in the arrangement of the various cooperating parts may be made without departing from the spirit or scope of the invention, as expressed in the following claims.

What I claim is:

1. A resilient pad structure comprising a member having grooves therein, a plurality of springs, and links connecting and securing said springs and disposed in said grooves.

2. A resilient pad structure comprising a member having a groove therein, a plurality of springs disposed over said groove and seated against the surface of the member, and means connecting said springs and disposed in said groove. 65

3. A resilient pad structure comprising a member having a groove therein, a plurality of springs disposed over said groove and seated against the surface of the member, means connecting said springs and disposed in said groove, and anchoring means for securing the end springs to said member. 70

4. In combination, a member having a groove therein, a plurality of springs having their bases seated against the outer surface of said member, and links connecting said springs and disposed in said groove. 75

5. In combination, an ironing roll having a circumferential groove therein, a plurality of springs having their bases seated against the surface of said roll, and means in said groove for securing the springs to the roll. 80

6. In combination, an ironing element having a circumferential groove therein, a plurality of springs having their bases seated against the surface of said element, and means in said groove for securing the springs to the element. 85

7. In combination, a member having a groove therein, a resilient pad structure secured to said member and comprising a plurality of sets of springs, each set comprising a pair of springs having their bases connected together, and means in said groove secured to and connecting said sets of springs. 95

8. In combination, a member having a groove therein, a resilient pad structure secured to said member and comprising a plurality of sets of springs, each set comprising a pair of springs having their bases connected together by an integral connecting member, and means in said groove secured to and connecting said sets of springs. 100

9. In combination, an ironing roll having a circumferential spiral groove therein, a plurality of springs having their bases seated against the surface of said roll, and means in said groove for securing the springs to the roll. 105

10. An ironing roll comprising a shell having a spiral groove in its outer surface, a plurality of springs arranged spirally around said shell over said groove, means in said groove securing said springs to each other, means in said groove securing the end springs to said shell, and a flexible covering surrounding said springs. 115

In witness whereof, I have hereunto set my hand this 7th day of December, 1927.

FRANK M. PRATT.
